UNITED STATES PATENT OFFICE.

JOHN E. SEDERHOLM, OF ST. PAUL, MINNESOTA, ASSIGNOR TO AMERICAN HOIST & DERRICK CO., A PARTNERSHIP COMPOSED OF F. J. JOHNSON AND W. O. WASHBURN, OF RAMSEY COUNTY, MINNESOTA.

MAGNETIC CHUCK.

Application filed August 2, 1924. Serial No. 729,806.

This invention relates to new and useful improvements in magnetic chucks designed particularly to hold and support a plurality of metallic articles such as castings, and the like, while being ground or machined, and more particularly relates to such chucks adapted to be mounted upon the usual reciprocating work table of an ordinary surface grinder, thereby to securely hold the work while being ground and finished.

Magnetic chucks, of ordinary construction, and such as are commonly employed at present, are not well adapted for use with surface grinders as a result of the prevalent danger of short-circuiting the coils or windings mounted therein, usually caused by water entering the chuck body and reaching the coils, it being necessary to have constant stream of water flowing over the work and grinding wheel of such a machine during the grinding operation. Magnetic chucks, to be successfully used in connection with surface grinders, must necessarily be of water-proof construction so as to positively prevent any water or moisture from entering the casing or body thereof and reaching the coils with the resultant short-circuiting and burning out of such coils.

The novel construction of the magnetic chuck features in this invention is such that it will be impossible for any water or moisture to enter the body and short-circuit the coils. It is also designed so as to reduce to a minimum the magnetic leakage. The construction of the chuck is very simple and is such that it may readily be mounted upon the usual work table of a grinder, in either a horizontal or vertical position. It is preferably provided with two complete magnetic circuits, thereby adapting it to hold and support a plurality of both large and small pieces of work for machining in one operation. The interior of the chuck is filled with a suitable insulating medium such as oil which functions to completely and thoroughly insulate the coils from all conductive material. The oil also functions to prevent moisture from entering the chuck-body and also to prevent the chuck from heating when in continuous operation.

The particular object of this invention therefore is to provide a powerful magnetic chuck of improved and simple construction, which may be efficiently used in conjunction

with an ordinary surface grinder or similar device, without the usual danger of water entering the chuck body and thus causing the coils or windings therein to short-circuit and burn out.

A further and more specific object of the invention is to provide such a device having an oil gauge or receptacle mounted thereon which is in communication with the interior of the chuck body to allow for expansion and contraction of the insulating medium, and which gauge is also located at a point above the chuck body so as to create a slight internal pressure therein, so that in case of a leak in the chuck body the oil will ooze or leak out, thereby preventing water from entering the chuck with the resultant ruination of the coils and windings.

Other objects of the invention will more fully appear from the following description and the accompanying drawings and will be pointed out in the annexed claims.

In the drawings there has been disclosed a structure designed to carry out the various objects of the invention but it is to be understood that the invention is not confined to the exact features shown as various changes may be made within the scope of the claims which follow.

In the accompanying drawings forming part of this specification,

Figure 1 is a view in side elevation of a portion of an ordinary surface grinder showing the improved chuck operatively mounted thereon;

Figure 2 is an enlarged plan view of the chuck removed from the grinder;

Figure 3 is a cross-sectional view on the line 3—3 of Figure 2;

Figure 4 is a similar view on the line 4—4 of Figure 2.

Figure 5 is a detail sectional view showing the connection of the reservoir with chuck chambers, and illustrating the adjustability of the reservoir.

The body of the novel chuck shown in the accompanying drawings comprises a rectangular metallic frame having end walls 11 and 12 and the side walls 13 and 14. A relatively smaller frame comprising end walls 15 and 16 and side walls 17 and 18 is mounted within the larger frame as shown in Figures 2, 3 and 4. These two frames are secured to a metallic base plate 19 by means

of screws 21 as shown in Figures 3 and 4. A bar 22, preferably of larger cross section than the sections of the two frames, is centrally mounted within the smaller rectangular frame and in like manner is secured to the plate 19 by means of similar screws 21. The walls of the two rectangular frames and also of the bar 22 mounted within the smaller frame constitute the positive and negative poles of the chuck. In the operation of the chuck these poles will be energized to attract the articles placed in contact therewith as will be hereinafter described.

15 The means provided for energizing or magnetizing the negative and positive poles of the chuck preferably consists in the mounting of a series of coils or windings in the space provided between the walls of the 20 two frames and also in the space between the bar 22 and the smaller rectangular frame. In the drawings there are two such coils shown, an outer coil 23 and an inner coil 24. These coils are preferably connected in series, and 25 current is supplied thereto through the conductors 25 and 26 mounted in a terminal box 27 suitably secured to the end wall 12 of the larger frame. A suitable non-magnetic material such as babbitt 28 is interposed between the upper edges of the walls 30 of the two frames as particularly shown in Figure 3. These upper edges of the two frames and also of the bar 22 are also preferably secured together by means of non-magnetic metal strips or bars 29 seated in 35 recesses 31 provided in the upper edges of the two frames and the bar 22 and are suitably secured thereto by means of countersunk screws 32. Thus it will be seen that 40 when the chuck is assembled as above described, the upper edges of the walls of the two frames and also of the central bar 22 will be flush with the upper surface of the babbitt 28 and also of the non-magnetic crossbars 29. In assembling this novel 45 chuck, the crossbars 29 are first secured to the edges of the two frames and to the central bar 22, thereby retaining the walls of the two frames and the bar in parallel spaced relation. The structure thus far assembled 50 is then placed on a face plate or other smooth surface with the bars 29 in contact therewith, after which the babbitt is poured into the spaces between the walls of the two frames and of the bar 22, thereby positively 55 sealing the upper portion of the chuck body against leakage, as is clearly shown in Figure 3. Longitudinal grooves 30 are preferably provided in the walls of the two frames and in the bar 22 into which the molten babbitt may flow to securely anchor it to the 60 walls of the two frames. The two coils 23 and 24 are then mounted in the chuck and the lower plate 19 secured to the bottom 65 edges of the two frames by means of the

screws 21, as shown. Wood spacing blocks 33 are preferably provided on each side of the two coils in order to prevent them from coming in direct contact with any metal of the chuck body. When the coils have thus 70 been positioned between the walls of the two frames and the central bar 22, and the lower plate 19 secured thereto, as above described, the coils 23 and 24 will be securely held in place within the body of the chuck. 75

In order to prevent water or moisture from entering the body of the chuck with the resultant danger of short-circuiting and therefore burning out of the coils, a suitable insulating medium such as oil is preferably 80 introduced in the spaces wherein the coils are mounted, thereby completely submerging the coils in an insulating oil with the result that it will be practically impossible for any moisture to come into direct contact with 85 the coils. To keep the body of the magnetic chuck completely filled with oil, a gauge 34 is preferably mounted in the end wall 12 of the larger frame as particularly shown in 90 Figures 2 and 5. This gauge is so arranged 95 with respect to the chuck body that the oil level therein will be above the upper wall or portion of the chuck and therefore above the oil level therein, thereby creating a slight internal pressure within the chuck body. 100 For the purpose of maintaining the reservoir in vertical position, whatever the working position of the chuck, the reservoir is adjustably connected with the delivery conduit as at 41, so that the same head or pressure can always be maintained within the 105 chuck and coil chambers. A suitable duct or ducts 40 are provided in the walls of the smaller rectangular frame of the chuck body in order that the oil may circulate between the two coil chambers. 110

In the operation of the magnetic chuck here shown, the chuck as a whole is placed upon the usual reciprocating work table 35 of an ordinary surface grinder as shown in Figure 1. In this figure, the chuck is shown mounted on the work table in a horizontal position beneath the grinding wheel 36, indicated in dotted lines. When it is desired to machine or surface-grind a number of castings or other articles, they will be placed upon the upper surface of the chuck as shown in Figure 2, each article being so placed thereon as to be in direct contact with a positive and negative pole, which will 115 thereby cause it to be securely held to the surface of the chuck as a result of the magnetic influence of the poles induced by the energization coils 23 and 24. As a result of the novel arrangement of the two rectangular frames and the central bar 22, and of the coils 23 and 24 mounted therebetween, the chuck will be provided with two 120 complete magnetic circuits. This is effected by means of the exposed edges of the two 125

frames and of the central bar 22 which function as positive and negative poles, the edges of the walls 11, 12, 13 and 14 of the larger frame and also the upper edge of the central bar 22 becoming the positive poles, and the upper exposed edges of the smaller frame becoming the negative poles. Thus when a metallic article is placed in contact with a positive and negative pole and current is passed through the coils 23 and 24, such article will be magnetically secured to the face of the chuck without danger of removal therefrom until the flow of current through the coils 23 and 24 has been interrupted.

15 In the operation of the chuck should a leak occur in the walls thereof, the internal pressure of the oil therein, caused by the oil level in the gauge 34 being above the level of the oil in the body of the chuck, will cause 20 the oil to ooze or leak out of the fracture in the chuck body, thereby preventing any water or moisture from entering therein and short-circuiting the coil. Such leakage of oil from the chuck body will also serve as 25 a warming to the operator that the body of the chuck has been injured, and it will therefore be repaired before serious damage can result. In addition to the oil within the chuck body functioning as insulating medium 30 for the coil and also to prevent moisture from entering therein it also functions as a means of holding down the temperature of the chuck when used continuously for a long period of time.

35 If desired, the chuck may be arranged on edge upon the reciprocating work table of the grinder as shown in dotted lines in Figure 1. When thus positioned, the gauge 34 will be rotated a quarter of a turn from that 40 shown in full lines in the same figure, thereby maintaining the oil level above the surface of the chuck body. Lugs 37 are preferably provided on the end walls 11 and 12 of the larger frame or body of the chuck to 45 provide means whereby the chuck may be securely clamped or fastened to the reciprocating work table 35 when positioned as shown in dotted lines in Figure 1.

I claim as my invention:

50 1. A device of the class described, comprising a pair of pole frames disposed one within the other, and spaced to provide an outer coil chamber between the frames, with the smaller frame providing an inner coil 55 chamber, a reinforcing pole plate disposed medially of the inner frame, of less length than the frame forming a coil support, a coil within each chamber, said outer frame having at its inner side adjacent one end, a circumferential groove, and said inner frame and pole plate having corresponding grooves 60 on both sides, moldable material forming plates sealingly closing and connecting the frames and pole plate by engagement with in the grooves, and a work-engaging face

plate detachably fastened to the opposite side of, and closing the frame.

2. A hollow chuck comprising two pole frames, one within the other, spaced apart to provide two intercommunicating coil 70 chambers, a pole plate disposed medially within the inner frame, magnetic coils, one in each chamber, the outer frame adjacent one side having a groove around its inner face and the inner frame and pole plate 75 having the corresponding grooves on both sides, and plates of moldable non-magnetic material in sealing engagement with the grooves, and a work-engaging plate detachably secured to and closing the opposite sides 80 of the frame.

3. A hollow chuck comprising two pole frames, one within the other, spaced apart to provide two intercommunicating coil chambers, a pole plate disposed medially within 85 the inner frame, magnetic coils, one in each chamber, the outer frame adjacent one side having a groove around its inner face and the inner frame and pole plate having the corresponding grooves on both sides, plates 90 of non-magnetic material in sealing engagement with the grooves, a work-engaging plate detachably secured to and closing the opposite sides of the frame, and a supply reservoir connected with the chuck and in 95 communication with the coil chamber supplying oil for completely filling the coil chamber, maintaining a head or pressure therein, and allowing expansion of the oil when heated.

4. A hollow chuck comprising two pole frames, one within the other, spaced apart to provide two intercommunicating coil chambers, a pole plate disposed medially 105 within the inner frame, magnetic coils, one in each chamber, the outer frame adjacent one side having a groove around its inner face and the inner frame and pole plate having the corresponding grooves on both sides, and plates of non-magnetic material molded 110 into sealing engagement with the grooves, a work-engaging plate detachably secured to and closing the opposite side of the frame, a supply reservoir connected with the chuck and in 115 communication with the coil chamber supplying oil for completely filling the coil chamber, maintaining a head or pressure therein, and allowing expansion of the oil when heated, during operation of the chuck, said reservoir adjustably arranged to be 120 maintained in vertical position whatever the working position of the chuck may be.

5. A reversible magnetic chuck, comprising a box-like chambered chuck body, having a work-engaging plate detachably joined thereto closing the chamber on one side, a magnetic coil within the chamber, an oil delivery conduit communicating with the chamber, and a combined oil reservoir and expansion chamber connected to, carried by 125 130

- and communicating with the conduit and arranged at a level above the chamber for obtaining and maintaining a head or pressure within the chamber about the coil to prevent 5 seepage of water through a broken joint in the coil chamber, whereby, if a joint in the chuck opens, the appearance of oil will indicate a need of repair, while at the same time water is prevented from entering.
- 10 6. A magnetic chuck, comprising a plural piece chuck body including a work-engaging plate detachably secured to and closing one side of the chuck having a plurality of inter-communicating coil-receiving chambers, an 15 oil delivery pipe communicating with the chambers, an oil reservoir adjustably connected with the oil pipe, and arranged above the level of the chamber for producing a

head or pressure within the chamber to prevent entrance of water thereto by seepage, 20 said reservoir movable with the chuck and adjustable to remain in vertical position above the chuck, whatever the working position of said chuck.

7. A magnetic chuck comprising frames 25 one within the other spaced to form coil chambers one about the other, and containing coils, pole bars on one side transversely connecting and securing the frames in spaced relation, moldable non-magnetic material 30 sealingly closing the frames about the bars, and a face plate detachably secured to and closing the frames at the opposite side.

In witness whereof, I have hereunto set my hand this 30th day of July, 1924.

JOHN E. SEDERHOLM.
